ABRADING TOOL

Fred W. Stachelrodt, Cicero, Ill., assignor to
Western Electric Company, Incorporated, New
York, N. Y., a corporation of New York

Application June 8, 1939, Serial No. 278,034

5 Claims. (Cl. 51—187)

This invention relates to abrading tools and more particularly to abrasive strip holders.

An object of this invention is the provision of an abrasive strip holder having simple and practical means for supporting and clamping an abrasive strip and for readily releasing and permitting movement of the strip on the holder to position another portion thereof for use.

In accordance with the above object, the present invention, in one embodiment thereof, provides an abrasive strip holder for use in hand polishing operations and the like, comprising a support member over a forward end face of which is folded an abrasive strip having its end portions strung along opposite faces of the member. The support faces are formed intermediate their ends with inwardly inclined portions extending toward the forward end face of the support member. The strip ends are threaded between the member and a spring actuated slideable clamping device comprising a sleeve carried on the member intermediate its ends. The sleeve has inner inclined faces cooperating with the inclined portions of the member for constantly drawing the strip taut and clamping the end portions thereof to the support member. Upon the abrasive strip becoming worn, it is released by a relative longitudinal movement between the clamping device and the support member against the action of the spring whereupon the strip may be freely drawn along the support member to reposition it. Thereafter, upon releasing either the support member or the clamping device the spring again causes the strip to be drawn taut and clamped to the support member.

Other objects and advantages of this invention will more fully appear from the following detailed description, taken in conjunction with the accompanying drawing, in which

Fig. 1 is a perspective view of an abrasive strip holder embodying the features of the invention;

Figs. 2 and 3 are fragmentary longitudinal vertical and plan sections, respectively, through the holder shown in Fig. 1, and

Fig. 4 is a vertical section taken on the line 4—4 of Fig. 2.

Referring to the drawing, the numeral 10 indicates a support member which may be of any suitable material such as aluminum, hard rubber, or phenolic resin. In the embodiment of the invention shown, the support member is in the form of a bar of hard fibre which is generally flat and of square cross-section throughout its length and is tapered upon two sides at its forward or working end, as indicated at 11, the op-

posite or rear end being used as a handle to be grasped by the user. The forward end is tapered to more readily permit its use where space is limited and to increase the visibility of the user in applying it. Intermediate the ends of the support bar 10 the two sides thereof, which are tapered, are formed with aligned inclined portions or cam faces 12 which extend inwardly from the plane of the sides toward the forward end face of the bar for a suitable distance and thence outwardly to the plane of the sides thereof.

Over the forward end face of the support bar 10 is folded an emery or abrasive ribbon or strip 13 having a width substantially the same as that of the support sides and having its end portions 14 strung along the two sides of the support which are tapered at their forward ends. Although in the drawing the abrasive strip 13 is shown as extending approximately to the rear or handle end of the support bar 10, it is to be understood that it may extend for any distance which is found suitable.

Slideable upon the rear end portion of the support bar 10 is a spring actuated clamping device 15. The clamping device includes in the particular embodiment illustrated a tapered sleeve having a U-shaped member attached thereto, the member having opposite arms 16 extending along two sides of the bar 10, which are disposed at right angles to the sides thereof which are tapered at their forward ends. Suitable clearance is provided between adjacent surfaces of the arms 16 and the sides of the bar to permit a free relative sliding movement therefrom. Interconnecting the arms 16 is a web 17 which is suitably spaced from the rear end face of the bar 10. Entered in an aperture in the handle end of the bar 10 is a compression spring 20, the spring being compressed between the inner surface of the web 17 and the inner end wall of the aperture. A screw 21 threaded into the web 17 with its inner end extending into the aperture and surrounded by the spring serves to maintain the spring in position.

At their forward ends the arms 16 are tapered and attached to these tapered portions by screws 22. Spaced arms 23 of a U-shaped member forming a part of the tapered clamping sleeve 15. An interconnecting web 24 extends between the arms 23 at one side of the bar and at the opposite side thereof a plate 25 is secured by brazing, soldering, or otherwise to the spaced edges of the tapered portions of the arms 16. The web 24 and the plate 25 are inclined at angles substantially similar to that of the opposite aligned cam faces 12 of the bar 10 and are suitably spaced

- therefrom. Thus opposite cam faces 26 are provided on the clamping device or sleeve 15 for cooperation with the cam faces 12. Upon the clamping device 15 and the bar 10 being permitted 5 to move longitudinally relatively to each other by the action of the compression spring 20 the end portions 14 of the abrasive strip 13 are drawn taut along opposite sides of the bar and clamped thereto.
- 10 Upon the strip 13 becoming worn in use it may readily be repositioned upon the bar 10 by first relatively longitudinally moving the bar 10 and the clamping device 15 against the action of the compression spring 20 to release the end portions 14 of the strip which are clamped between the cooperating cam faces 12 and 26 of the bar 10 and the device 15, respectively. While thus released, one or the other of the end portions 14 of the strip 13 may be grasped and freely drawn 15 along the support bar 10 to position unworn portions of the strip along the forward side faces of the bar. Thereafter, upon releasing either the support bar 10 or the clamping device 15 the compressed spring 20 will again cause the strip 13 to be drawn taut and clamped to the bar 10.

From the foregoing description, it will be apparent that an abrasive strip holder is provided having simple and practical means whereby abrasive strip strung thereon may be clamped thereto 20 and constantly held taut, and which may be readily released and moved thereon to position another portion thereof for use without removing parts of the holder or the use of tools.

It will be understood that the embodiment 30 herein described is merely illustrative of the invention and one application thereof, the invention being limited only by the scope of the appended claims.

What is claimed is:

- 40 1. An abrasive strip holder comprising a support member for an abrasive strip folded over an end face thereof and having its end portions strung along opposite portions of the member, said portions of the member having inclined faces 45 intermediate their ends, means slidable upon the support member and having inclined faces cooperating with the inclined faces of the support member for engaging the end portions of the strip, and means operatively associated with the 50 slidable means and support member normally effective to urge said inclined faces into cooperating operative relation to draw the strip taut and clamp it to the support member.
- 55 2. An abrasive strip holder comprising a support member for an abrasive strip folded over an end face thereof and having its end portions strung along opposite portions of the member, said opposite portions of the member having inclined faces intermediate their ends, a member 60 slidable upon encircling the support member and the end portions of the strip and having inclined faces cooperating with the inclined faces of the support member for engaging the end portions of the strip, and means operatively arranged be-

tween the slidable means and support member normally effective to urge said inclined faces into cooperating operative relation to draw the strip taut and clamp it to the support member.

3. An abrasive strip holder comprising a bar 5 for supporting an abrasive strip folded over an end face thereof and having its end portions extending along and abutting opposite generally flat sides of the bar, said sides of the bar intermediate their ends having aligned inclined faces, 10 a member slidable upon the bar and having inclined faces cooperating with the inclined faces of the bar for engaging the end portions of the strip, and means operatively arranged between the member and the bar normally effective to 15 urge said inclined faces into cooperating operative relation to draw the strip taut and clamp it to the bar.

4. An abrasive strip holder comprising a bar 20 having a pair of opposite faces generally flat 25 throughout their length for supporting an abrasive strip folded over an end face thereof and having its end portions extending along said opposite faces of the bar, said faces having intermediate their ends inwardly inclined portions extending toward said end face of the bar, a sleeve member slidable upon the bar and having inclined portions cooperating with the inclined portions of the bar for engaging the end portions 30 of the strip, an element secured to said sleeve member and extending freely along faces of the bar other than said flat faces and across and spaced from an opposite end face of the bar, and means arranged between said latter end face of the bar and an opposed face of said element 35 normally effective to urge said inclined portions into cooperating operative relation to draw the strip taut and clamp it to the bar.

5. An abrasive strip holder comprising a bar 40 of generally square cross-section for supporting an abrasive strip folded over an end face thereof and having its end portions extending along opposite sides of the bar, said sides of the bar having aligned inwardly inclined faces extending toward said end face of the bar, a sleeve member 45 slidable upon, encircling the bar and the end portions of the strip and having opposite inclined faces cooperating with the inclined faces of the bar for clamping the end portions of the strip therebetween, a U-shaped member having parallel portions and an interconnecting portion, said parallel portions secured to parallel portions of said sleeve and extending along side faces of the bar disposed at right angles to said before mentioned sides of the bar, said interconnecting portion 55 extending across and spaced from an end face of the bar, and a compression spring arranged between the end face of the bar and the interconnecting portion of the U-shaped member normally acting to urge said inclined faces into 60 cooperating operative relation to draw the strip taut and clamp it to the bar.
